Primary Examiner — Holly E Thurman*Assistant Examiner* — Danielle Nichole Bowly*(74) Attorney, Agent, or Firm* — Sughrue Mion, PLLC(57) **CLAIM**

The ornamental design for a writing instrument as shown and described.

DESCRIPTION

FIG. 1 is a perspective view of a writing instrument showing my new design;

FIG. 2 is a front view thereof; a rear view being a mirror image;

FIG. 3 is a top view thereof;

FIG. 4 is a bottom view thereof;

FIG. 5 is a left side view thereof;

FIG. 6 is a right side view thereof; and,

FIG. 7 is cross-sectional slice with an internal mechanism omitted thereof, taken along line 7-7 in FIG. 3.

The broken lines illustrate portions of the writing instrument and form no part of the claimed design.

1 Claim, 3 Drawing Sheets(56)
